FOLDED SHEET AND METHOD OF FOLDING THE SAME

Filed April 8, 1931

UNITED STATES PATENT OFFICE

1,996,307

FOLDED SHEET AND METHOD OF FOLDING
THE SAMESamuel Shapiro, New York, N. Y., assignor to
Olga Liben, Bronx, N. Y.

Application April 8, 1931, Serial No. 528,467

2 Claims. (Cl. 206—57)

My invention relates to the folding of sheets of material, such as paper, used for napkins, towels and the like, and the same has for its object to produce a sheet folded so as to facilitate the removal thereof from a stack of such folded sheets, particularly when the stack is disposed in a dispensing device.

Another object of the invention is to provide an article of the character specified in which the folds thereof are arranged to render the article substantially uniformly resilient or flexible to facilitate the removal thereof from the stack.

Another object of the invention is to provide an article of the character specified in which the parts are folded so that all exposed edges are folded edges and the article can be withdrawn from the stack without unfolded edges of the sheet forming the same being exposed and interfering with or being injured by the withdrawal.

Another object of the invention is to provide an article of the character specified in which the coextensive and lesser sections are arranged in symmetrical or balanced relation and form an article having continuously smooth uninterrupted outer surfaces.

Other objects will in part be obvious and in part be pointed out hereinafter.

In the drawing:

Figure 1 is a perspective of one form of article constructed according to and embodying my said invention, with the end shown spread apart.

Fig. 2 is an end view of the article, looking at the spread out end thereof; and

Fig. 3 is a perspective of the sheet spread out to show the creases therein.

The sheet 10, as shown in Fig. 3, comprises six coextensive portions or sections 12 having predetermined equal dimensions and four lesser portions or sections 14 of reduced width compared to the width of each portion 12, the width of the portions 14 preferably being less than one-half the width of the portions 12.

The sheet 10 is folded in one direction on the line 16 to bring the panel 14a into overlapping relation to the remaining portion of the sheet and is folded in the opposite direction on the line 18 to bring the panel 14b into overlapping relation to the opposite side of the remaining portion of the sheet. The sheet 10 is then reversely folded on the lines 20 and 22 to bring the panels 12a, 12b and 12c into overlapping relation. The panels 12a and 12b are folded so that the panel 14a is disposed therebetween, and panels 12b and 12c are folded so that the panel 14b is disposed therebetween. The overlapping panels are then folded

along the line 24 to complete the folded article.

The sheet 10 is preferably of tissue paper or the like employed for napkins and towels. The coextensive sections 12 are preferably of predetermined dimensions so that the article will fit the dispensing device. The lines of fold 16, 18, 20 and 22 are therefore so taken as to enable formation of sections 12 of the desired size, the portion of the sheet 10 intermediate the folded edge portions or panels 14a and 14b forming the sections 12, while the sections 14 are formed from such surplus edge portions 14a and 14b. With this method of folding, the sheets can come in various widths without changing the width of the folds or panels 12a, 12b and 12c, the additional width being taken care of by change in the width of the panels 14a and 14b. The line of fold 24 is preferably along the middle of the sheet so that all the sections 12 are coextensive, all the side edges are folded edges, and the exposed raw edges of the sheet are brought together at one end of the article.

In the article thus formed coextensive sections 12 form the exposed surfaces of the article so that each surface is continuous and uninterrupted, offering minimum impedance to withdrawal of the article from the stack. The panels 12a, 12b and 12c are folded in zigzag formation with the panels 14a and 14b disposed between the coextensive panels in unexposed position, and such coextensive panels comprise an odd number 30 so that the panels 14a and 14b can be disposed in symmetrical or balanced relation relative to the coextensive panels or sections, or in off-set relation to each other.

The forward edge 26 and sides of the folded article are devoid of raw sheet edges, the lines of fold or return bends between successive sections or panels being located along the sides of the article, and constituting the lateral margins of all the folds or sections. Such return bends are less subject to wear and offer less resistance to the withdrawal of the article from the stack or dispensing device than a folded article having exposed raw edges.

When the article is folded flat the total thickness thereof is equal to 8 plies, including each pair of offset sections 14. The panels 14a and 14b are made of a width less than one half the width of the panels 12a, 12b, or 12c so that the edges of the former will not overlap and cause increase of 50 thickness at the center. Up to such limit the panels 14a and 14b may vary in width to take care of surplus width of sheet.

The folded article as described is inherently

resilient or flexible so that the forward edge portion 26 can be uniformly flexed for facilitating the removal thereof from the stack or dispensing device such as disclosed in my copending application Serial No. 459,920 filed June 9, 1930. The opposite outside surfaces of the folded article are formed from the front side of the sheet while the opposing or contacting innermost surfaces are formed from the rear side of the sheet, said outside and innermost surfaces being coextensive and continuous and no raw edges being exposed so that the article can be readily removed from the stack without danger of tearing or otherwise injuring the same. By my invention I am able to apply a flexing pressure to the folded article at the uppermost side thereof, relative movement of the innermost relatively smooth coextensive surfaces, brought into contact by folding at 24, being facilitated, resulting in the flexing of the front portion 26 of the article as a whole to allow its ready removal from a stack.

Having thus described my invention what I claim and desire to secure by Letters Patent is:

1. A folded paper article having single-thickness edge parts reversely folded on lines adjacent and parallel to its side edges, and an odd number of coextensive parts all of equal width intermediate

between the edge parts and at least twice as wide as the edge parts and reversely folded on equi-spaced lines parallel to the edges to bring the coextensive parts into overlapping relation with the edge portions extending inwardly therebetween, and the sheet, so folded and overlapping, folded together on a line parallel to the end edges, whereby all side edges are folded edges, all exposed raw edges are at the end of the article opposite the last named fold, and the exposed surfaces are the full width of the folded article. 5 10

2. A folded paper article having single-thickness edge parts reversely folded on lines adjacent and parallel to its side edges, and three coextensive parts all of equal width intermediate between the edge parts and at least twice as wide as the edge parts and reversely folded on equi-spaced lines parallel to the edges to bring the coextensive parts into overlapping relation with the edge portions extending inwardly therebetween, and the sheet, so folded and overlapping, folded together on a line parallel to the end edges, whereby all side edges are folded edges, all exposed raw edges are at the end of the article opposite the last named fold, and the exposed surfaces are the full width of the folded article. 15 20 25

SAMUEL SHAPIRO.
